(57) **CLAIM**

What is claimed is the ornamental design for a bottle with applicator, as shown.

DESCRIPTION

The proposed invention is a bottle with applicator for containing and applying correction fluid.

FIG. 1 is a perspective view of a bottle with applicator, embodying my new design;

FIG. 2 is an exploded perspective view thereof;

FIG. 3 is a front elevation thereof;

FIG. 4 is a side elevation view thereof;

FIG. 5 is a top plan view thereof;

FIG. 6 is a bottom plan view thereof;

FIG. 7 is a perspective view of the applicator, shown separately for ease of illustration;

FIG. 8 is a top plan view thereof;

FIG. 9 is a front elevation view thereof; and,

FIG. 10 is a bottom plan view thereof.
